UNITED STATES PATENT OFFICE.

WILLIAM WEBSTER, OF LONDON, ONTARIO, CANADA, ASSIGNOR TO
EDWARD K. WARREN, OF THREE OAKS, MICHIGAN.

MACHINE FOR TREATING QUILL SUBSTANCE.

No. 836,420.

Specification of Letters Patent.

Patented Nov. 20, 1906.

Application filed November 14, 1904. Serial No. 232,757.

To all whom it may concern:

Be it known that I, WILLIAM WEBSTER, a subject of the King of Great Britain, residing at London, in the Province of Ontario, Canada, have invented certain new and useful Improvements in Machines for Treating Quill Substance, of which the following is a specification.

This invention relates to machines for treating quills in the manufacture of what is commercially known as "featherbone," a substance designed to fill the office of flexible resilient stays in connection with various classes of dress goods. In the preparation and manufacture of quills into articles of this nature the quill is first split and then thoroughly stripped of its contained pith. Thereafter the longitudinal sections of the quill thus cleaned are "fibered"—that is, further split longitudinally into a number of thin narrow slivers or fibers lying side by side, with the end portions of successive bunches of fibers overlapped and intermixed, so as to create a continuous line of substantially uniform caliber, to which is applied a winding or covering of thread to mechanically bind the fibers together. Thereafter the strip thus created is immersed in a specially-prepared glue or cement and then dried, which imparts a uniformity of structure and strength, cohering all the parts together into a practically integral mass and at the same time preserving the natural elastic quality or resiliency of the original material. Thereafter the strip is often provided with a cloth or other covering, whereupon it is fitted to serve the general purposes of an elastic stay. In the practical manufacture of this substance as at present carried out the splitting of the quills, the stripping of the pith therefrom, the fibered of the split and cleaned sections, and the wrapping or winding of the fibered quills have generally been performed by separate machines in separate and distinct operations, thus requiring the expenditure of considerable time and the services of a large number of operators in the practical manufacture of the substance on a considerable scale.

My present invention has for its general and principal object to facilitate the manufacture of the material described by combining the performance of the several operations hereinabove described in a single ma-

chine in which these several operations may be rapidly and successively carried out, whereby to economize in respect to both the time required for the manufacture of a given quantity of material and also in respect to the labor and expense therein. 60

Briefly stated, therefore, my invention may be said to reside in a machine for treating quills wherein the splitting of the quills, the elimination of the pith, the fibered, and the wrapping or winding are all performed 65 successively in the order named, the machine also including a mechanism for feeding the quills successively to the splitting mechanism, intermediate means for passing the quills on from one mechanism to the next, 70 and mechanism for receiving and laying the wound product on suitable rollers or spools.

In the accompanying drawings I have illustrated a machine capable of carrying out the operations described and embodying my invention in the best mechanical form which I have thus far devised after numerous tests and experiments, and, referring thereto— 75

Figure 1 is a top plan view of the complete machine. Fig. 2 is a similar view, on an enlarged scale, with the winding and spooling mechanism omitted. Fig. 3 is a side elevational view of the machine with the spooling mechanism omitted. Fig. 4 is a front elevational view of the machine. Fig. 5 is a top 80 plan view of the main table or platform, showing the main shaft with parts of the driving mechanism of the pith-cutters and fibered devices above the same and a diagram of the underlying gears which actuate the feed-rolls 85 of the winders. Fig. 6 is an enlarged detail view, in front elevation, of the fibered or slivering mechanism and the devices for actuating the same. Fig. 7 illustrates in side elevation a convenient arrangement of overhead 90 belt-and-pulley driving mechanism for imparting motion directly to the main shaft and the pith-cutter shafts of the machine. Fig. 8 is an enlarged edge elevational view of the quill-feeding mechanism. Figs. 9 and 10 are 95 detail edge and plan views of one of the duplicate peripherally-flattened quill-feeding disks constituting a part of the quill-feeding mechanism. Fig. 11 is a diagrammatic plan view of the intermeshing gears underlying 100 the bed-plate of the machine and driving the rotating elements of the superposed quill feeding and fibered devices. Fig. 12 is a front 105

itudinal sectional view through the spooling mechanism, illustrating the friction-drive for the spools. Fig. 13 is a detail elevational view, partly in section, of the feeding mechanism of the winders. Fig. 14 is a detail side elevational view of the means for separating the feed-rolls of said winder-feed mechanism. Fig. 15 is a detail vertical sectional view through the fibering or slivering mechanism 10 with the cutters thereof appearing in edge elevation. Figs. 16, 17, 18, and 19 are respectively top plan, bottom plan, front edge, and rear edge views of the lower partition-plate of the fibering mechanism. Fig. 20 is a 15 cross-sectional view on the line 20 20 of Fig. 16. Fig. 21 is a top plan view of a pair of spacers and underlying cutters such as are employed between the lower partition-plate and the upper partition-plate. Figs. 22, 23, 20 24, and 25 are respectively top plan, bottom plan, front edge, and rear edge views of the upper partition-plate of the fibering mechanism; and Fig. 26 is a top plan view corresponding to Fig. 21 of the spacers and 25 underlying cutters employed above the upper partition-plate.

Before proceeding to a detail description of the machine I will first briefly outline in a general way the organization of the machine, 30 naming the several mechanisms and the order in which they coöperate. The entire mechanism is superposed upon a flat horizontal table or platform, the principal operating parts of the machine being carried by a bed-plate supported on suitable standards upon and above said table or platform. At one end of the supporting-frame is mounted a quill-feeding mechanism from which the stripped quills are advanced one at a time 35 upon a quill-splitting blade, whence the two halves of the quill are fed in opposite directions past a pair of rotary cutters, which clean the inner surfaces of the quill-sections of the pith. Thence the cleaned sections are 40 advanced, one in a substantially direct line and the other by a roundabout course, so as to cause them to overlap longitudinally, between a pair of feed-rolls and a longitudinal guide-channel to the action of a fibering or 45 slivering mechanism which splits the quills longitudinally into a mass of fibers or slivers and immediately thereafter divides the mass of fibers or slivers thus formed into a plurality of separate bundles which are led off independently into and through the throats or 50 receiving-tubes of a series of winders situated at different angles behind and converging toward the discharge side of the fibering mechanism. In these winders the several bundles of fibered stock are wound about by a suitable thread to bind them together into a continuous cord, the winders themselves being provided with feed-rolls which serve to draw the cords through the winders at a suitable rate of speed to effect the proper winding. 55

From the winders the wound cords pass rearwardly of the machine over a reciprocating guiding mechanism to and around a series of receiving-spools, on which they are wound in successive layers. 70

Proceeding now to a detailed description of the machine and of the several coöperating mechanisms of which it is composed, 1 designates a rectangular horizontal table or platform supported at its four corners on legs 2. 75

3 designates a horizontal bed-plate supported upon and above the table 1 on standards 4, most of which are omitted from the drawings for the sake of greater clearness. 80

Describing first the quill supporting and feeding mechanism, 5 designates a horizontal lateral extension of the bed-plate 3 from which rise at longitudinally-separated points pairs of inner and outer guide-rods 6 and 7, respectively, the two rods of each pair being 85 spaced sufficiently to receive between them a stack made up of a series of superposed stripped quills 8. Inwardly of the guides 6 there rises from the bed-plate a post 9, which has a deep longitudinal groove 10 on that side 90 adjacent to the guides 6, the lower end of which groove is continued through the post in the form of a feed-slot 11 of sufficient size to admit the passage therethrough of the lowermost of the series of quills. The post 9 95 is preferably surmounted by a removable guide-hopper 12, having outwardly-flaring walls adapted to readily receive and guide into the vertical groove of the post the advance or blunt ends of the quills. From the foregoing it will be seen that the stack of 100 quills is supported and guided at its inner end by the grooved post 9 and intermediate its length by the inner and outer guide-posts 6 and 7. 105

In order to effect the downward feed of the individual quills of the stack as fast as each lowermost quill is withdrawn, I employ means for maintaining a constant downward pressure on the stack of quills, the means herein shown for this purpose consisting of a bar 13, disposed behind the stack and having pivoted to the ends thereof fingers 14, which overlie the upper quill crosswise thereof, to which bar is secured a depending rod 15, passing through and guided in the bed-plate extension 5 and platform 1 and terminating in a weight 16. 110

In order to make the bar 13 readily retractible past a fresh stack of quills, the fingers 14 115 are normally spring-pressed downwardly or inwardly toward the plane of the bar 13 by springs 17, their movement in the opposite direction under the action of the weight resisted by the quills being limited by stoppins 18, Figs. 2 and 8. This construction 120 enables a fresh stack of quills to be loaded into the quill-holder and the quill-depressing bar to be subsequently raised and engaged with the uppermost quill, the rounded upper 125 130

edges of the fingers 14 riding idly against the inner sides of the quills during such upward movement.

Describing next the mechanism for feeding forward into the machine the successive quills of the stack as fast as each assumes the lowermost positions, 19 and 19^a designate a pair of duplicate feed-rolls that are mounted in the same horizontal plane on the upper ends 10 of shafts 20 and 20^a, journaled vertically in the bed-plate 3. These disks, as more particularly shown in Figs. 8, 9, and 10, are provided with grooved peripheries 19^b, and each has a portion of such grooved periphery cut 15 away or flattened, as shown at 19^c. The disks are so positioned in the horizontal plane of the feed slot or throat 11 that the lines of their maximum peripheries coincide or contact in the path of movement of the lowermost 20 quill, as clearly shown in Fig. 2, whereby as the rear ends of the flattened portions 19^c come together upon the quill the latter is clamped between the grooved peripheries of 25 said disks and advanced thereby until the other ends of the flattened portions coincide, thus bringing said flattened portions opposite each other and releasing the tail of the quill. From the slot or throat 11 the nose of 30 the quill enters the grip of a pair of feed-rolls 21 21^a, mounted in the same horizontal plane on the upper surface of the bed-plate 3, said rolls being keyed on the upper ends of a pair of vertical shafts 22 22^a, mounted in the bed-plate 3. From the grip of said rolls the quill 35 passes directly upon the point of a knife-blade 23, adjustably held by a set-screw 24 in a supporting-block 25, so as to lie longitudinally of the advancing quill and centrally of its path of movement, whereby the quill is 40 split longitudinally into halves. One of these halves, making a turn of substantially a right angle to the right, is engaged by and fed between the feed-roll 21 and a companion feed-roll 26, keyed on the upper end of a 45 shaft 27, vertically journaled in the bed-plate 3, whence it passes between the periphery of a rotary cutter-head 28 and a guide-block 29 opposite the periphery of said cutter and adjustable toward and from the latter by a set-screw 30, mounted in a fixed block 31 and engaging the guide-block 29. The rotary cutter-head 28 is keyed on the upper end of a shaft 32, journaled vertically in the bed-plate 3. On the opposite side of the knife 23 50 is a feed-disk 26^a, mounted on a vertical shaft 27^a and co-operating with the feed-disk 21^a to carry forward the left-hand half of the split quill into the field of action of a rotary cutter-head 28^a, mounted on a vertical shaft 55 32^a and co-operating with a guide-block 29^a, adjustable toward and from the periphery of the cutter by means of set-screw 30^a, mounted in the stationary guide-block 31^a. The parts 21 to 32 and 21^a to 32^a, respectively, hereinabove described are duplicates and per-

form similar operations upon the split halves of the quill, their function being to advance the latter and thoroughly clean it of its contained pith by the action of the cutters 28 and 28^a. The directions of rotation of the 70 cutter-disks are indicated by the arrows placed thereon, from which it will be seen that the quill-engaging portion of each cutter travels in the same direction as the quill itself, the cutting-disks being provided with 75 oblique peripheral teeth which effectually eat out the body of pith contained in each half of the quill.

From the pith-cutter 28 the cleaned half of the quill passes through a tubular guide-channel 33 to the nip of another pair of peripherally-milled-corrugated feed-rolls 34 and 34^a, keyed on the upper ends of shafts 35 and 35^a, respectively, rotatively mounted in the bed-plate 3, and from the rotary pith-cutter 28^a the other half of the cleaned quill advances 80 through a curved tubular guide 36 between a pair of forwarding feed-rolls 37 and 37^a, keyed on the upper ends of shafts 38 and 38^a, whence it is passed through another tubular 85 guide 39, so disposed relatively to the companion guide 33 as to form with the latter convergent paths for the two halves of the cleaned quills, which merge at the discharging 90 ends of the guides opposite the nip of the 95 said feed-rolls 34 and 34^a. The tubular guides 33 and 39 are preferably secured to the bed-plate 3 in a manner to render them capable of accurate positioning relatively to each other and to the parts which they connect by means of base-flanges 33^a and 39^a, extending laterally therefrom and secured to the base-plate, as by screws 40 and 41, respectively. The two cleaned halves of the 100 quill which meet at the convergent end of the 105 channel-guides 33 and 39, pass thence one partially in advance of the other, into and through a further tubular guide 42, located beyond the feed-rolls 34 and 34^a, with its longitudinal axis substantially tangential to the 110 contacting peripheries of said feed-rolls. The guide 42 is adjustably secured to the bed-plate by means of a slotted laterally-projecting base-flange 42^a, through which passes a set-screw 43. One roll of each of the several pairs of feed-rolls above described is 115 preferably mounted in an adjustable bearing-block set in and constituting, essentially, a part of the main bed-plate of the machine, for the purpose of nicely adjusting the spacing of the companion rolls of each pair and their grip on the stock passed between them. For instance, the roll 26^a is mounted in a block 44, rendered adjustable toward and from the 120 companion roll 21^a by an adjusting-screw 45. The rolls 37^a and 26 are mounted in a similar bearing-block 46, rendered adjustable toward and from the companion rolls 37 and 21, respectively, by an adjusting-screw 47, and, similarly, feed-roll 34^a is mounted in a 125 130

bearing-block 48, adjustable horizontally toward and from the companion roll 34 by means of an adjusting-screw 49.

In order to prevent clogging of the operating parts by the excised material represented chiefly by the removed pith, I preferably provide means adjacent to the pith-cutters 28 and 28^a for producing a suction effect for the removal of such waste material as fast as it is separated from the shell. The means herein shown for this purpose consists of a suction-tube 50, connected at one end with a suitable exhaust-fan (not shown) and at its other end with the outer end of a channel 51, cored in the bed-plate 3 and terminating in the space immediately adjacent to the cutter 28. From the space immediately surrounding the periphery of the companion cutter 28^a a branch suction-duct 52 leads around and beneath the front portion of the machine to a junction with the main suction-conduit 50, all as clearly shown in Fig. 2. A constant suction being maintained through the pipes 50 and 52, the chips and dust are drawn away as fast as formed.

From the guide 42 the split quills pass to the action of the fibering mechanism, which splits the quills longitudinally into a mass of slivers or fibers, which as they emerge from this mechanism are divided into a plurality of bundles, each of which is led away separately to and through a mechanism which wraps a thread therearound to bind them into a continuous cord. This fibering mechanism consists, generally speaking, of two stacks of superposed rotary cutting-disks separated by alternate stationary washers, which serve the double function of spacing the cutting-disks so that the edges of one series slightly overlap the proximate edges of the other series and of cleaning the cutting-disks and preventing the accumulation of fine particles of the material therebetween. The construction of this mechanism will be readily understood by reference to the detail views, Figs. 15 to 26, inclusive, wherein 53 and 54 designate a pair of vertical shafts rotatably mounted in the bed 3 beyond and to either side of the discharge end of the guide 42, said shafts having keys 53^a and 54^a, respectively. To either side of said shafts are mounted in the bed pairs of posts 55 and 56, respectively. On the shaft 53 is mounted, first, a washer 57 and above the same a series of alternately-disposed circular cutting-disks 58 and spacers or cleaners 59. On the companion shaft 54 is mounted, first, a washer 60 and above the latter a corresponding series of alternately-disposed cutter-disks 61 and spacers or cleaners 62. Directly above the lowermost cutters on the shafts 53 and 54 is mounted what I term the "lower" partition-plate, the same being shown in detail in Figs. 16 to 20, inclusive. This member 65 consists of a pair of symmetrical flat wings

59^a and 62^a, which correspond in form and function to the spacers 59 and 62, connected by a bridge 63. The lower flat side of the bridge has the form shown in bottom plan in Fig. 17, having a forwardly or inwardly extending point 64, which lies between the adjacent sides of the wings 59^a and 62^a. The bridge also has on its upper surface an upstanding narrow V-shaped wall 65, thereby creating a pair of outwardly-divergent channels 66 and 67.

It will be observed by reference to Figs. 18, 19, and 20 that the wing 62^a is mounted the thickness of one of the cutter-disks lower than the plane of the companion wing 59^a. This is in accordance with the general arrangement of the cutters and spacers throughout the stack wherein the cutters on one side lie in the horizontal planes of the spacers on the other, thus allowing the overlapping of the adjacent edges of the cutter-disks.

At substantially mid-height of the stack is interposed what I term the "upper partition-plate." This is shown in detail in Figs. 22 to 25, inclusive, and consists, like the lower partition-plate, of a pair of symmetrically-disposed wings 59^b and 62^b, connected by a bridge 68. The form and construction of this latter are here illustrated in top plan in Fig. 22 and in bottom plan in Fig. 23, where in it will be seen that this bridge also has a sharp inwardly-extending point 69 lying between the adjacent sides of the wings 59^b and 62^b. The formation of the under side of this plate adapts it to seat directly upon the upper surface of the wall 65 of the lower partition-plate while its upper surface is formed to present a pair of outwardly-divergent channel-guides 70 and 71 leading off from the apex 72 of a vertical dividing-wall constituting the upright walls of the channels 70 and 71. The several cutting-disks 58 and 61 are keyed on the shafts 53 and 54, respectively, and rotate therewith, while the spacing-washers, as also the wings of the lower and upper partition-plates, are provided with apertures by which they fit over the posts 55 and 56 as well as with central apertures sufficiently large to fit over the shafts 53 and 54 and the key-feathers thereon, from which it will be understood that the spacers and partition-plates are held against rotation. Comparatively thick washers 73 and 74 overlie the two stacks of cutters, respectively, which latter are clamped with the requisite pressure to insure a clean shearing action between the co-operating edges of the cutting-disks by nuts 75 and 76, retained by locking-nuts 77 and 78, respectively, screwed down on the upper ends of the shafts 53 and 54.

From the foregoing it will be seen that the upper surface of the base-plate of the bridge 63 in association with the wall 65 on one side and the edges of the interposed spacers and wings of the lower partition-plate make up

the confining walls of the intermediate channels 66 and 67, which divide vertically and guide off in two horizontally-divergent sections substantially the lower half of the 5 fibered or slivered stock delivered by the fibering mechanism, while the corresponding elements of the bridge 68 of the upper partition-plate in association with the inwardly-adjacent edges of the superposed spacers 10 make up the widely divergent channels which divide vertically the upper half of the fibered stock and guide the separated portions away in substantially opposite directions.

From the fibering mechanism last described 15 the divided sections of the fibered stock pass off to and through a series of winders which wind about them a binding cord or thread. These winders, which are duplicates of each other and are positioned 20 on the table 1 at suitable relative angles to receive the several sections, are each mounted on a post 79, secured at its base by the clamping-bolt 80, operating in a slot 81^a of a horizontal foot 81 in such a manner as to be adjustable 25 in the direction of its length toward and from the fibering mechanism. The post 79 has rotatably mounted on a tubular shaft projecting inwardly from a bracket 82, connected to its upper end, a pulley 83, on the 30 inner face of which are mounted spools 84, carrying the winding-thread 85. Attached to the inner face of each pulley 83 concentrically therewith and in alinement with its tubular shaft is an inwardly-projecting tube 35 86, which extends into close proximity to the several discharging-channels of the fibering mechanism, being preferably outwardly flared or enlarged at their inner ends, as shown at 86^a, to facilitate the entrance of the stock to 40 be wound. The threads 85 from the spools are threaded through small holes 87 in the tube 86 just in rear of the enlargement 86^a thereof. On the upper end of the post 79 is mounted, side by side, a pair of gripping and 45 feeding rolls 88 and 89, Fig. 13, the function of which is to grip the wound cord, draw it through the winders, and pass it on to the receiving-reels. One of these rolls (88, as herein shown) is fast on the upper end of a shaft 90, 50 rotatably mounted in the head of the post 79, said shaft extending downwardly through a bearing in the table 1, Fig. 3. The roll 88 carries on its upper end a small gear 91, which meshes with a small gear 92 on the companion roll 89 and drives the latter. In order to 55 separate said rolls when desired, the roll 89 is made adjustable toward and from its companion driving-roll 88 by being mounted on a short vertical shaft 93, that is set in a horizontally-slidable block 94, inwardly pressed by a spring 95, carried in a laterally-projecting casting 96. To force the block 94 outwardly, a small crank-arm 97, Fig. 14, is mounted in the head of the post opposite the inner end of 60 the block 94 and provided with a flattened 65

side 97^a bearing against the latter. By giving the crank-arm 97 a quarter-turn the block 94 is forced outwardly in an obvious manner, thus separating the rolls.

From the winders the wound strips may 70 be carried to and received upon any suitable receiving-reels or spools, the mechanism herein shown for this purpose being as follows: In a pair of bracket-arms 98, secured to and extending rearwardly from the table 1, 75 is journaled a reel-shaft 99, Fig. 12, carrying on one overhanging end a grooved pulley 100, by which it is driven. Keyed on this shaft are a series of friction-disks 101 and 102, and loosely mounted on the same between said 80 disks are a series of receiving-spools 103. One head of each spool is crowded against the respective disks 101 by means of a coil-spring 104, which at one end thrusts against the other head of the spool, its opposite end having an adjustable abutment against the disk 102, whereby the thrust of the spring may be 85 regulated to secure the required frictional effect between the opposite head of the spool and its coöperating friction driving-disk 101. 90 By adjusting the tension of the springs 104 the required degree of drag may be imparted to the spools to create such a tension on the strips wound thereon as will serve to lay the material in close and compact order, yet 95 without danger of interrupting the continuity of the strip at any stage in its passage through the machine. In order to lay the strips in close and uniform coils, I have shown merely 100 a well-known type of coiling mechanism consisting of a sleeve 105, slideable longitudinally on a rod 106, supported parallel with and beyond the receiving-spools, this sleeve carrying a series of grooved pulleys 107, one for each spool over which the wound strips are passed 105 and having at one end the usual tongue 108, that rides back and forth in a right and left hand thread formed on one end of the shaft 106.

Thus far I have described the various 110 mechanisms and instrumentalities that perform the successive operations upon the material treated, transforming it from stripped quills at the start to continuous uniform strips or cords of the fibered shells of the 115 quills. I will now briefly describe the mechanism by which the several operating parts already described are given their respective movements and caused to perform their respective functions in the operation of the machine. 120

Referring first to Figs. 3, 5, and 7, horizontally journaled upon the table 1 and beneath the bed 3 is the main driving-shaft of the machine, (designated by 109,) which shaft carries 125 on its overhanging end a grooved pulley 110, receiving motion from a belt 111, herein shown as driven from a pulley 112 on an overhead shaft 113, suspended by hangers 114 from the ceiling. This shaft 109 has formed 130

thereon a worm 115, running upon an oil tablet or cushion 116 and meshing with a worm-wheel 117, Fig. 6, fast on the shaft 53 of the fibering mechanism, whereby the left-hand set of cutters is positively driven. A master-gear 118, also fast on the shaft 53, meshes with and drives a companion gear 119 on the lower end of the shaft 54, whereby the right-hand set of cutters is driven at the same rate 10 of speed and in the opposite direction to the rotation of the left-hand set of cutters.

Referring next particularly to Figs. 11 and 2, the former of which shows in diagram the gears underlying the bed 3 and driving the 15 various movable parts mounted above said bed shown in Fig. 2, the gear 118 drives an idler-gear 120, which in turn drives a gear 121 on the lower end of the shaft 35 of the feed-roll 34. Gear 121 drives a companion gear 20 122 on the lower end of the shaft 35^a of the companion feed-roll 34^a, and it also drives a large idler 123, which drives a gear 124 on the lower end of the shaft 20 of the flattened quill-feeding disk 19, gear 124 driving a companion gear 125 on the lower end of the shaft 20^a of the companion quill-feeding disk 19^a. The idler-gear 123 also drives a gear 126 on the lower end of the shaft 22 of the feed-roll 21, and the gear 126 drives a companion gear 30 127 on the lower end of shaft 22^a of the companion feed-disk 21^a. Three small intermeshing gears 128, 129, and 130, on the lower ends of feed-roll shafts 27, 38, and 38^a, respectively, drive the several feed-rolls 26, 37, and 35 37^a, respectively, while a small gear 131 on the lower end of shaft 27^a drives the feed-roll 26^a. The pith-cutters 28 and 28^a, being required to rotate at a high rate of speed, are 40 preferably and as herein shown independently driven, the means for such purpose consisting of pulleys 132 and 133, fast on the lower ends of the shafts 32 and 32^a of said cutters, engaged by independent driving-belts 134 and 135, Figs. 3, 5, and 7, driven from pulleys 136 and 137 on the overhead shaft 45 113, said belts being guided around a pair of end pulleys 138 and 139 and an intermediate double-grooved pulley 140, all suitably mounted on a pair of standards 141, secured 50 to the table 1.

Referring next to the means for driving the series of winders, 142 and 143 designate a pair of double-grooved pulleys fast on the main shaft 109, the former of which, by belts 55 144 and 145 and suitable idler guide-pulleys 146, drive the pulleys 83 of the two intermediate winders, while the latter, through belts 147 and 148, Fig. 1, and suitable idler guide-pulleys 149, drive the corresponding pulleys 60 of the two outside or lateral winders.

For the purposes of driving the several sets of feed-rolls 88 and 89, which draw the wrapped strips through the winders, I provide on the lower end of the shaft 53 of the 65 fibering mechanism beneath the table 1 a

master-gear 150, Fig. 6, which through the train of gears indicated by dotted lines in Fig. 5 drives the several shafts 90 of the feed-rolls 88, this train of gearing being as follows: On one side the master-gear 150 meshes with 70 an idler-gear 151, which in turn meshes with and drives an outside and intermediate gear 152 and 153 on the lower ends of the two roll-shafts 90 on one side of the machine. On the other side the master-gear similarly 75 drives an idler 154, which in turn meshes with and drives an outside and intermediate gear 155 and 156, respectively, on the lower ends of the roll-shafts 90 on the opposite side of the machine. 80

The reel-shaft 99 is driven by an endless belt 157 engaging the pulley 100 and receiving its motion from a horizontal pulley 158, fast on the lower face of the master-gear 150, as clearly shown in Fig. 6, the two sections of 85 said belt being guided around idler guide-pulleys 159 and 160, secured to the under side of the table 1, as clearly shown in Fig. 5.

The shaft 113 of the overhead driving mechanism (which latter it will be understood does not constitute any essential part of the present machine, but is intended merely to illustrate a convenient means for applying power thereto) is provided, as shown in Fig. 7, with fast and loose pulleys 90 161 and 162, respectively, engaged by a belt 163, driven from any suitable source of power, an ordinary belt-shifter 164, operated by a depending lever 165, being employed to shift the belt for starting and stopping the machine. 95

In some cases it is found desirable, although not necessary, to provide a continuous central core for the several wound strips produced by the machine. For this purpose I 105 have shown the present machine as equipped with a thread-guide 166, consisting of a horizontally-extending bar on the upper end of and preferably integral with a standard 167, secured on the front end of the table or 110 platform 1, said bar having a series of slotted thread-guides 168, Fig. 4, to receive and support core-threads 169 led therethrough from a series of spools, (not shown,) which may be mounted on any suitable support sufficiently 115 in advance of the machine-frame to be out of the way of its operating parts. From the guide 166 the threads extend above the operating parts of the machine directly into the mouths of the several winder-tubes 86 centrally of the fibered stock. The employment of such core-threads affords greater tensile strength to the wound or wrapped strips in cases where special tensile strength is required or desired. 120

The operation of the machine has been to a considerable extent already indicated, but may be briefly recapitulated as follows: With the quill-depressing device in its lowest position, in which it rests upon the lateral exten- 125 130

sion of the bed 3, the stripped quills are stacked up in the quill-guide, after which the weighted quill-depressing device is elevated until the fingers 14 overlie the topmost quill, 5 as shown in Fig. 2. Power being then applied by shifting the main driving-belt 163 to the tight pulley motion is communicated to the movable parts of the various coöperating mechanisms of the machine. Thereupon the 10 quill-feed rolls 19 and 19^a seize upon the lowest quill and clamping it frictionally between their grooved peripheries advance the point of the quill through the throat 11 into the nip of the auxiliary feed-rolls 21 and 21^a, whence 15 the point of the quill emerges upon the vertical cutting edge of the splitting-knife 23. From the latter one-half of the quill passes onto the right between the feed-rolls 21 and 26 and thence past the cutter 28, with its pith 20 side engaged by the teeth of the latter, whereby the quill is thoroughly denuded of the pith, the latter being drawn off as fast as it is separated through the suction-tube 50, 25 the cleaned quill passing thence through the channel-guide 33 into the nip of the feed-rolls 34 and 34^a. The other half of the split quill passes to the left through the feed-rolls 21^a and 26^a past the pith-cutter 28^a, where it is denuded of the pith, the latter being drawn 30 away through the suction branch 52. Thence the cleaned section turns back on itself in the channel-guide 36, being thence further advanced by the auxiliary feed-rolls 37 and 37^a into and through the channel- 35 guide 39, whence it emerges alongside of but approximately half its length in rear of its companion half-section of the quill. Meanwhile the quill-feed rolls 19 and 19^a have seized upon the next lowermost quill and advanced the latter in close order through the 40 same mechanism. In this manner the cleaned quill-stock is passed through the feed-rolls 34 and 34^a in successive half-shell sections so disposed that the joints on one 45 side are brought substantially opposite the longitudinal center of the half-shell sections on the other, thereby producing such an overlapping of the joints as produces a substantial continuity in the stock considered as a 50 whole and prevents any breaks or gaps therein. From the feed-rolls 34 34^a the reunited sections of the quills pass side by side through the guide 42 into and through the fiberizing or 55 slivering mechanism, wherein the shells are cut longitudinally into a series of comparatively fine fibers or slivers, which being forced endwise upon the vertical dividing edges of the lower and upper partition-plates, as well as upon the horizontal dividing edge formed 60 by the pointed central portion of the bridge of the upper partition-plate, is divided into four approximately equal sections, which are thence directed off through the angularly-disposed guides of said partition-plates into and 65 through the throats or mouths of the tubular

guides of the winders. Immediately upon their entrance to said guides the winding or wrapping threads are wound about the stock, thereby securing the fibers or slivers together and insuring the continuity of the several 70 cords. From the winders the wound cords pass through the drawing-rolls 88 89, which latter thereupon become effective to assist the previously-acting series of feed-rolls in passing the stock along through the successive 75 mechanisms. From the drawing-rolls 88 89 the wound cords as fast as formed are carried over the spooling-guides 107 and then attached to the hubs of the spools, whereupon the frictional rotation of the latter 80 serves to wind the finished cords thereupon with sufficient tensional effect to prevent slack between the spools and the drawing-rolls and lay the cords upon the spools as fast as they are delivered by the machine. 85 The pull of the spools is regulable by proper adjustment of the collars 102, which determine the tension of the springs 104 on the spooling-shaft, and consequently determine the degree of rotative frictional effect imparted to the spools by the collars 101. 90

Practically all of the several mechanisms which operate upon the stock are provided with means, as already described, whereby their speed and intimacy of contact with the 95 stock may be nicely regulated and adjusted, this being important, since the relative movements of the several mechanisms must be accurately timed and slip between the stock and the parts engaging the same avoided in 100 order to prevent both bunching or undue enlargement on the one hand and attenuation or interruption in the continuity of the stock on the other and maintain the finished product of substantially uniform caliber. 105

It is evident that the machine as hereinabove described, and illustrated in the drawings, might be considerably modified in respect to the construction and relative disposition of the several operating parts, as well 110 as by the substitution of mechanical equivalents, without departing from the spirit and principle of the invention or sacrificing any of the advantages thereof. Hence I do not limit the invention to the particular mechanism shown and described except to the extent indicated in specific claims. 115

I claim—

1. In a quill-treating machine, the combination with mechanism for reducing the 120 quills to a mass of slivers or fibers, of a winding mechanism receiving the fibered mass from the fiberizing mechanism and wrapping a binding cord or thread around said mass, substantially as described. 125

2. In a quill-treating machine, the combination with mechanism for reducing the quills to a mass of fibers, of a winding mechanism receiving the fibered mass from the fiberizing mechanism and wrapping a binding- 130

thread around said mass to form a cord, and gripping - rolls serving to draw the cord through said winding mechanism, substantially as described.

5 3. In a quill-treating machine, the combination with a mechanism for reducing the quills to a mass of fibers, of a winding mechanism receiving the mass and wrapping a binding-thread therearound to form a cord, 10 gripping - rolls serving to draw the cord through said winding mechanism, and means for winding said cord upon a suitable receiving-spool, substantially as described.

4. In a quill-treating machine, the combination with a mechanism for reducing the quills to a mass of fibers, of a winding mechanism receiving the fibered mass and wrapping a binding-thread therearound to form a cord, a receiving-spool on which said cord is 15 wound, and means for frictionally driving said receiving - spool, substantially as described.

5. In a quill-treating machine, the combination with means for reducing the quills to 20 a plurality of separated bundles of slivers or fibers, of means adapted to receive said bundles and apply a suitable winding about each of the same, substantially as described.

6. In a quill-treating machine, the combination with means for reducing the quills to 25 a plurality of separated bundles of slivers or fibers, of a corresponding plurality of winders adapted to receive said bundles and wind about each of them a binding-thread, substantially as described.

7. In a quill-treating machine, the combination with means for reducing the quills to 30 a mass of slivers or fibers, and means located opposite the discharge-point of such fibering

40 mechanism serving to divide the mass longitudinally, of means located adjacent to the discharging-points of such dividing mechanism serving to apply a suitable winding about each of the separated bundles to form a cord, 45 substantially as described.

8. In a quill-treating machine, the combination with means for reducing the quills to 50 a mass of slivers or fibers, and means located opposite the discharge-point of such fibering mechanism serving to divide the mass longitudinally, of a plurality of winders located adjacent to the discharging-points of such dividing mechanism and adapted respectively to receive the divided sections of the 55 fibered stock and wind about each of them a binding-thread to form a cord, substantially as described.

9. In a quill-treating machine, the combination with means for reducing the quills to 60 a mass of slivers or fibers, of means located opposite the discharge-point of such fibering mechanism serving to divide the mass longitudinally, a plurality of winders located adjacent to the discharging-points of such dividing mechanism and serving to respec-

tively wrap a binding-thread around the divided sections of the fibered stock to form a cord, and gripping-rolls serving to draw the fibered and wrapped cord through the winding mechanisms, substantially as described. 70

10. In a quill-treating machine, the combination with means for reducing the quills to a mass of slivers or fibers, of means located opposite the discharge-point of said fiberizing mechanism, serving to divide the mass longitudinally, a plurality of winders located adjacent to the discharging-points of said dividing mechanism and serving to respectively wrap a binding cord or thread around the divided sections of the fibered mass to form a 80 cord, gripping-rolls serving to draw the cord through the winding mechanism, a series of receiving - spools, means for winding said wrapped cord upon said spools, and means for frictionally driving said receiving-spools, 85 substantially as described.

11. In a quill-treating machine, the combination with a fiberizing mechanism, of mechanism for dividing the fibered mass longitudinally into a series of separated sections, 90 winders for wrapping a binding-thread around said sections to form a cord, and means for coiling said wrapped sections upon suitable receiving-spools, substantially as described.

12. In a quill-treating machine, the combination with a fiberizing mechanism, of mechanism for dividing the fibered mass longitudinally into a series of separated sections, winders for wrapping a binding - thread around said sections to form a cord, gripping- 95 rolls serving to draw the fibered and wrapped cord through the winders, and means for winding said cords upon suitable receiving-spools, substantially as described. 100

13. In a quill-treating machine, the combination with a mechanism for reducing the quills to a mass of fibers, of mechanism for dividing the mass longitudinally into a series of separated sections, winders for wrapping a binding-thread around said sections to form 105 a cord of each, gripping-rolls serving to draw the fibered and wrapped cords through the several winders, respectively, a series of receiving-spools, means for winding said cord upon said receiving-spools, and means for 110 frictionally driving said receiving-spools, substantially as described.

14. In a quill-treating machine, the combination with mechanisms for splitting, cleaning, and fiberizing the quills, of means for 115 dividing the mass of fibers formed from said quills longitudinally into a plurality of continuous bundles, a corresponding plurality of winders adapted to wrap a binding-thread around said bundles to form cords, a corresponding plurality of gripping-rolls serving to draw said cords through said winders, means for driving said fiberizing mechanism, and driving connections from the latter to 120 said gripping-rolls, substantially as described. 130

15. In a quill-treating machine, the combination with mechanisms for splitting, cleaning, and fibering the quills, of means for dividing the mass of fibers longitudinally into 5 a plurality of continuous bundles, a corresponding plurality of winders adapted to wrap a binding-thread around said bundles to form cords, a main driving-shaft, driving connections from said shaft to said fibering 10 mechanism, and other driving connections from said shaft to said winders, substantially as described.
16. In a quill-treating machine, the combination with two coöperating series of rotary fibering-disks for reducing the quills to a 15 mass of fibers and operating-shafts on which they are mounted, feeding devices therefor, means for dividing the mass of fibers produced thereby into a plurality of continuous 20 bundles, a corresponding plurality of winders adapted to wrap a binding-thread around said bundles to form cords, gripping-rolls serving to draw said bundles to form cords through said winders, a spooling-shaft, and a 25 series of spools frictionally driven therefrom, of a main driving-shaft, driving connections therefrom to a shaft of the fibering mechanism, driving connections from the latter to said quill-feeding devices, gripping-rolls, and 30 spooling-shaft, and other driving connections from said main shaft to said winders, substantially as described.
17. In an organized mechanism for producing a fiber cord from quills, the combination 35 of mechanism for splitting the quills, mechanism for depithing the split sections, mechanism for resplitting said split sections to produce the fiber, and mechanism for wrapping the fiber, substantially as described.
18. In an organized mechanism for producing a fiber cord from quills, the combination 40 of mechanism for splitting the quills, mechanism for feeding the quills successively to said quill-splitting mechanism, mechanism for depithing the split sections, mechanisms 45 for resplitting the said split sections to produce the fiber, and mechanism for wrapping the fiber to form cord, substantially as described.
19. In an organized mechanism for producing a fiber cord from quills, the combination 50 of mechanism for splitting the quills, mechanism for depithing the split sections, mechanism for resplitting said split sections to produce the fiber, mechanism for dividing 55 the fiber longitudinally, and mechanism for wrapping the divided sections of fiber to form cord, substantially as described.
20. In an organized mechanism for producing a fiber cord from quills, the combination 60 of mechanism for splitting the quills, mechanism for feeding the quills successively to said quill-splitting mechanism, mechanism for depithing the split sections, mechanism 65 for resplitting the said split sections to produce the fiber, mechanism for dividing the fiber longitudinally, and mechanism for wrapping the divided sections of fiber to form cords, substantially as described.
21. In an organized mechanism for producing a fiber cords from quills, the combination 70 of mechanism for splitting the quills, mechanism for depithing the split sections, mechanism for effecting a longitudinal displacement of one section relatively to its 75 companion section, mechanism for resplitting the said split sections to produce the fiber, and mechanism for wrapping the fiber, substantially as described.
22. In an organized mechanism for producing a fiber cord from quills, the combination 80 of mechanism for splitting the quills, mechanism for depithing the split sections, mechanism for effecting a longitudinal displacement of one section relatively to its 85 companion section, mechanism for resplitting said split sections to produce the fiber, mechanism for dividing the fiber longitudinally, and mechanism for wrapping the divided sections of fiber, substantially as de- 90 scribed.
23. In a quill-treating machine, the combination of suitable means for supporting a stack of superimposed quills; yielding means for compressing the same toward the bottom 95 of the stack; a pair of auxiliary feed-rolls arranged transversely of the stack, said feed-rolls having flattened corresponding sides which permit the entry of a quill between the rolls from the bottom of the stack; feed-rolls 100 for receiving and advancing the quill; a vertical knife arranged between and beyond the rolls against which the quill is delivered to split it into halves; roughened feed-rolls for grasping the halves of the quill, coacting with 105 the feed-rolls at each side to advance the halves of the quill forwardly through the machine; suitable curved guides for receiving the respective halves of the quill and guiding the same as it is advanced by the roll- 110 ers, the said curved guides being each less in length than the length of the quill to be operated upon; cutter-heads arranged to act against the pith sides of the said halves of the quill respectively; feed - rolls to engage the 115 split quill and advance it forwardly to deliver the halves together in overlapping relation between suitable corrugated feed-rolls; corrugated feed-rolls to advance the halves together; rotary slitting-knives intermesh- 120 ing with each other for slitting the quill into a mass of fibers, arranged beyond the said corrugated feed - rolls; dividing - plates with passage-ways thereon for dividing the mass of quill fiber into bundles and distributing it 125 at different points; suitable winders with projecting tubular throats arranged opposite the mouths of the delivery-passages to embrace the cord and wind the same; and suitable frictional devices for drawing the 130

wound cord through the winders and delivering the same to suitable rolls or spools, all coacting substantially as described and for the purpose specified.

- 5 24. In a quill-treating machine, the combination of suitable means for feeding the quills; feed-rolls for receiving and advancing the quill; a vertical knife between and beyond the rolls against which the quill is delivered, to split it into halves; roughened feed-rolls for grasping the halves of the quill, co-acting with the feed-rolls at each side to advance the halves of the quill forwardly through the machine; suitable curved guides
10 for receiving the respective halves of the quill and guiding the same as it is advanced by the rollers, the said curved guides being each less in length than the length of the quill to be operated upon; cutter-heads arranged
15 to act against the pith sides of the said halves of the quill respectively; feed-rolls to engage the split quill and advance it forwardly to deliver the halves together in overlapping relation between suitable corrugated feed-rolls; corrugated feed-rolls to advance the halves together; rotary slitting-knives intermeshing with each other for slitting the quill into a mass of fibers, arranged beyond said corrugated feed-rolls; dividing
20 plates with passage-ways thereon for dividing the mass of quill fiber into bundles and distributing it at different points; suitable winders with projecting tubular throats arranged opposite the mouths of the delivery
25 passages to embrace the cord and wind the same; and suitable frictional devices for drawing the wound cord through the winders and delivering the same to suitable rolls or spools, all coacting substantially as described and for the purpose specified.

25. In a quill-treating machine, the combination of the main feed-rolls for receiving and advancing the quill; a knife arranged beyond the said feed-rolls and parallel therewith, for splitting the quill into halves; feed-rolls for grasping the halves of the quill, co-acting with the main feed-rolls at each side to advance the halves of the quill forwardly through the machine; suitable curved guides
30 for receiving the respective halves of the quill; cutter-heads arranged to act against the pith side of the halves of said quill respectively; feed-rolls to engage the said split quill beyond the cutter-heads and advance it forwardly to deliver the two halves together in overlapping relation; suitable corrugated feed-rolls for grasping the quills; rotary slitting-knives intermeshing with each other for slitting the quill into a mass of fiber, arranged beyond the said corrugated feed-rolls; dividing means for dividing the mass of fibers into bundles; and winders with projecting tubular throats to receive the bundles

of fibers directly from the guiding means, to form cords therefrom, all coating substantially as described and for the purpose specified. 65

26. In a quill-treating machine, the combination of a feeding device; of a knife for splitting the quill into halves; feed-rolls for grasping the halves of the quill to advance the halves of the quill forwardly through the machine; suitable curved guides for receiving the respective halves of the quill; cutter-heads arranged to act against the pith sides of the halves of said quill respectively; feed-rolls to engage the split quill beyond the cutter-heads and advance it forwardly to deliver the two halves together in overlapping relation; suitable corrugated feed-rolls for grasping the quill; rotary slitting-knives intermeshing with each other for slitting the quill into a mass of fiber, arranged beyond the said corrugated feed - rolls; dividing means for dividing the mass of fiber into bundles; and winders with projecting tubular throats to receive the bundles of fibers directly from the guiding means, to form cords therefrom, all coacting substantially as described and for the purpose specified. 70 75 80 85 90 95

27. In a quill-treating machine, the combination of a feeding device; a knife for splitting the quill; feed-rolls for grasping the quill, to advance the quill forwardly through the machine; suitable curved guides for receiving the quill; cutter-heads arranged to act against the pith side of the quill; feed-rolls to engage the quill beyond the cutter-heads; rotary slitting-knives intermeshing with each other for slitting the quill into a mass of fiber; dividing means for dividing the mass of fiber into bundles; and winders with projecting tubular throats to receive the bundles of fibers directly from the guiding means, to form cords directly therefrom, all coacting substantially as described and for the purpose specified. 95 100 105

28. In a quill-treating machine, the combination of a feeding device; a knife for splitting the quill; feed-rolls for grasping the quill, to advance the quill forwardly through the machine; suitable guides for receiving the quill; cutter-heads arranged to act against the pith side of the split quill; rotary slitting-knives intermeshing with each other for slitting the quill into a mass of fiber; and winder means with projecting tubular throat to receive the fibers directly from the guiding means to form cords therefrom, all coacting substantially as described and for the purpose specified. 110 115 120
